UNITED STATES PATENT OFFICE.

WILLIAM F. DEWEY, OF KANSAS CITY, MISSOURI.

STOVE CONSTRUCTION.

1,279,521.

Specification of Letters Patent. Patented Sept. 24, 1918.

Application filed December 16, 1916. Serial No. 137,288.

To all whom it may concern:

Be it known that I, WILLIAM F. DEWEY, a citizen of the United States, residing at Kansas City, in the county of Jackson and 5 State of Missouri, have invented certain new and useful Improvements in Stove Constructions, of which the following is a full and exact specification.

The present invention relates to heating 10 stoves, and aims to provide an improved knock-down construction whereby the parts of the same may be readily disconnected to occupy a small compass, and as readily and conveniently assembled and set up in position for use when desired.

It is also an object to devise an extremely 15 neat construction especially adapted for, though not confined to, stoves of the gas burning type, and one which will be of strong and serviceable character and inexpensive to manufacture.

A further object is to provide a stove of such arrangement and construction that the same may be readily adapted for either heating 20 or cooking purposes as circumstances may require. Minor objects and advantages will appear in the course of the detailed description.

With the general objects in view the invention will now be described with reference 25 to the accompanying drawings, illustrating one form of construction which has been devised for embodying the improvements, after which those features and combinations deemed to be novel will be set forth and defined in the appended claims.

In the drawings—

Figure 1 is a view in front elevation of a 30 stove constructed in accordance with the present invention;

Fig. 2 is a vertical section on the line II—II of Fig. 1;

Fig. 3 is a plan view of the burner stand 40 portion of the device, with the flame spreader element shown in altered position.

Figs. 4 and 5 are sectional views, on a larger scale, taken on the lines IV—IV and V—V, respectively, of Fig. 2;

Fig. 6 is an enlarged sectional view, taken 45 on the line VI—VI of Fig. 3;

Fig. 7 is an enlarged broken perspective view of one of the column members;

Fig. 8 is an enlarged and fragmentary perspective view of a pair of the panel sec-

tions of the stove casing, illustrating their 55 interengaging portions but in separated relation;

Figs. 9 and 10 are top plan views of said panel sections;

Fig. 11 is an inverted perspective view of 60 the top section of the stove casing, shown on a reduced scale;

Fig. 12 is an inverted plan view of one 65 of the upper corner brackets or socket pieces; and

Fig. 13 is a plan view of one of the lower corner brackets or socket pieces.

Referring to the drawings in detail, the stove is illustrated as of substantially rectangular cross section, with the burner 70 stand portion of the device shown as comprising a top plate portion 2 positioned within a skeleton frame 4 and connected thereto by the spider ribs 6, leaving the air passages 8 about the margin of said plate 75 portion 2. The skeleton frame 4 is provided with the projections 10 secured by bolts 12 to the corner legs 14, which are formed with lugs 16 for removably supporting a downward-radiation deflector plate 18 80 at a suitable distance above the floor, or other surface used for supporting the stove. To the frame 4 is also secured by bolts 20, at the rear of the stove, a hanger 22 for supporting the pipe connection 24 leading to 85 the burner 26, which projects through a central opening 28 in the deflector plate 18 up to within a suitable distance of the plate 2. The plate 2 is formed with a central opening 30 overlying the burner 26, which 90 opening is fitted with a flame spreader plate 32 adapted to rest upon the margin of said opening to close the same (as shown in Fig. 2), as when it is desired to spread the flame entirely below said plate 2. The margin of 95 the plate 32 is formed with a series of notches 34 adapted to accommodate the adjacent ends of the ribs 6 when said plate 32 is resting upon the margin of and closing said opening 30, whereas the plate 32 is of a 100 diameter such that when it is raised and partially turned the edges thereof may be rested upon said adjacent ends of the ribs 6 to support the plate 32 slightly above said opening 30 as shown in Figs. 3 and 6, thus 105 allowing the flame from the burner to pass through the opening and be spread by said plate 32 above said opening.

The stove casing is made up in sections comprising side panels 36 at the front and rear of the stove, side sections or panels 38 at the opposite ends thereof, and a top section 40. The panels 36 and 38 are perforated with openings 42 arranged according to any preferred pattern, and the top section may be provided with an opening 44 fitted with a cap or closure member 46. The margin of the top section 40 is formed with the down-turned rolls 48, and the lower edges of the side panels 36 and 38 are formed with similar out-turned rolls 50, and the upper ends of said panels are provided with inturned flanges 52 adapted to be fitted in overlapped relation against the under face of the top section 40 when the parts are assembled with said upper ends of the panels embraced within the space 55 closed by the rolls 48 of said top section. The vertical margins of the side panels 38 are provided with the out-turned flanges 54 which are adapted to be slidingly interengaged with the doubled flanges 56 formed 60 on the vertical margins of the panels 36 (see Fig. 8), the said panels 36 and 38 being assembled by relative endwise movement thereof, as will be readily understood. For embracing the corners at each of the 65 joints between said panels 36 and 38, as well as for producing a neat effect, the same are provided with column members 60 made of sheet material of approximately tubular form and having the inturned flanges 62, 70 one of which flanges is adapted to be slidingly inserted in any one of said joints within a channel or groove formed between the corresponding flange 56 and panel 38, the other of said flanges 62 resting upon the 75 other corner face of said joint as illustrated in Fig. 4.

At each of the upper corners of the stove casing is provided a bracket in the form of a socket piece 64 (see Fig. 12) having the 80 laterally opening sockets 66 for receiving the ends of the marginal rolls 48 at that corner, and also having a downwardly opening socket 68 for receiving the upper end of the corresponding column member 60. Each 85 socket piece 64 is provided with a perforated lobe portion 70 resting flat upon the top face of the top section 40 and secured thereto by a bolt 72, which also passes through openings 71 in the flange 52. The lower 90 corners of the stove casing are also provided with brackets in the form of somewhat similar socket pieces 73 (see Fig. 13), each having laterally opening sockets 74 for receiving the ends of the marginal rolls 50 of that corner, and with an upwardly opening socket 76 for embracing the lower end of the corresponding column member 60. Said socket pieces 73 are formed with perforated ears 78 for securing the same by means of stove 95 bolts 80 to the side panels as shown in Fig. 1.

At the front of the burner stand is provided a pair of curved supporting lugs 82 which are secured to the front legs of the stand by means of slotted ears 84 and bolts 86 (see Fig. 5). Similar curved supporting lugs 88, but of more nearly closed form, are provided at the rear of the burner stand. The lugs 82 and 88 are of curved outline for engagement with the lower marginal rolls 50 of the casing, and the arrangement and 100 contour of the supporting lugs are such that, when the casing is rested with said rolls upon the lugs, the casing will automatically settle to bring the rear marginal roll into retaining engagement with the more nearly closed lugs 88, due to the front marginal roll 50 being engaged by the curved lugs 82 and thereby urging the casing rearward as it settles down into horizontal position. For 105 retaining the casing in supported position, the front marginal roll 50 is provided with a pivotal sliding latch member 90 which extends upward within the casing in position to engage the outer projecting end of one of the ribs 6 at the top of the burner stand, 110 being engaged and disengaged from said rib by simply sliding the latch member in the proper direction along said marginal roll.

It will thus be apparent that a neat and simple construction has been devised for 115 carrying out the desired objects of the invention. One disadvantage of the ordinary form of stove construction is that so much space is required for shipping and storage, especially as regards the casings or drums, 100 and a higher shipping rate is demanded for the assembled type. The present improvements provide a construction which may be readily knocked down and all the parts placed together within a space of comparatively small compass. When shipped in this manner a lower freight rate may be taken advantage of, and moreover the dealer is not taxed for so much room in taking 110 care of a considerable number of the stoves. No special degree of skill or effort is required for assembling the parts of the stove, and when set up a light and yet substantial and durable construction of very neat and attractive design is produced. When the 115 casing is placed upon the burner stand it at once settles into proper position on the supporting lugs for latching the casing on the stand. The casing may be readily and conveniently removed from the burner stand 120 when desired to use the latter as a "hot plate" for cooking, and the flame spreader element 32 affords a simple device for regulating the spreading of the flame either entirely below the plate 2 or through and above 125 said plate 2 and around said spreader element.

While the foregoing illustrates what is now deemed to constitute the preferred form of embodiment of the improvements, the 130

right is reserved to all such formal changes or modifications as may fairly fall within the scope of the appended claims.

I claim:—

5. 1. In a knock-down stove construction, the combination of a casing formed in sections having portions detachably interengaging and adapted to retain the sections in assembled condition and providing a
10 channel between each pair of interengaged portions and the adjacent face of one of said sections, and column members mounted in detachable engagement with said sections at said interengaging portions and having
15 marginal flanges slidably engaging said channels.

2. A knock-down stove construction comprising a casing formed in sections having portions detachably interengaging and adapted to retain the sections in assembled condition and providing a channel between each pair of interengaged portions and the adjacent face of one of said sections, and column members mounted in detachable engagement with said sections at said interengaging portions, each of said column members being formed with a pair of marginal flanges, one flange of each column member fitting slidably in the channel corresponding to said column member and the other flange of ~~each~~ column member bearing upon the outer face of the other adjacent section.

3. A knock-down stove construction comprising a casing made up in sections forming side panels and a top section, said side panels having side marginal portions interengaging detachably and adapted to retain the sections in assembled condition, column members mounted in detachable engagement with said interengaging portions, socket members carried by the outer margin of said top section, the top portions of said panel sections being formed with inwardly projecting and overlapping flanges, and
40 bolts detachably connecting said socket members with said top section and said overlapping flanges.

4. In a knock-down stove construction, the combination of a casing made up in sections forming side panels and a top section, said top section having marginal roll portions and said side panels having detachably interengaging portions and adapted to retain the sections in assembled condition, column members arranged in detachable engagement with said interengaging portions, and members mounted at the upper ends of said column members and having socket portions for embracing said upper ends of the
55 column members and the marginal roll portions of said top section.

5. In a knock-down stove construction, the combination of a casing made up in sections forming a top section and also side panels
60 having detachably interengaging portions

and adapted to retain the sections in assembled condition, column members arranged in detachable engagement with said interengaging portions, said top section and the lower edges of said side panels having marginal roll portions, and members mounted at the upper and lower ends of said column members and having socket portions for embracing said upper and lower ends of the column members and said marginal roll portions.

6. A stove construction comprising a stand provided with a burner, a casing removably mounted upon said stand over the burner and inclosing the top portion of the stand, a
70 latch member carried by the lower edge of one side of said casing and adapted to engage said top portion of the stand, and means formed on the stand for detachable engagement with the lower edge of the opposite side of said casing for coöperation with said latch member in securing the casing to the stand.

7. A stove construction comprising a stand provided with a burner, a casing removably mounted upon said stand over the burner and inclosing the top portion of the stand, said stand being provided with curved supporting lugs at opposite sides thereof and said casing having lower edges of roll form
90 adapted to fit in said lugs, the lugs at one side of the stand being more nearly closed than at the other side whereby the casing on being supported on the lugs will automatically settle into retaining engagement by
95 said more nearly closed lugs, and means for latching the casing in supported position.

8. A stove construction comprising a burner stand, a casing removably mounted upon said stand and inclosing the top portion thereof, said stand being provided with curved supporting lugs at opposite sides thereof and said casing having lower edges of roll form adapted to fit in said lugs, the lugs at one side of the stand being more
105 nearly closed than at the other side whereby the casing on being supported on the lugs will automatically settle into retaining engagement by said more nearly closed lugs, and a latch member carried by the lower
110 edge of the casing on the side supported by the more open lugs in position to engage the top portion of said stand and hold said casing in supported position.

9. A stove construction comprising a
120 burner stand, a casing removably mounted upon said stand and inclosing the top portion thereof, said stand being provided with curved supporting lugs at opposite sides thereof and said casing having lower edges
125 of roll form adapted to fit in said lugs, the lugs at one side of the stand being more nearly closed than at the other side whereby the casing on being rested on the lugs will automatically settle into retaining engage-
130

ment by said more nearly closed lugs, means permitting the adjustment of the lugs at one side of the stand, and means for latching said casing in supported position.

- 5 10. A stove construction comprising a burner stand, a casing removably mounted on said stand and the latter being provided with means for detachably engaging the lower edge of one side of said casing, and
10 means for holding said side of the casing in engagement with said engaging means and latching the opposite side of said casing.

11. A stove construction comprising a burner stand, a casing removably mounted on said stand, said stand being provided with hook lugs at opposite sides thereof and said casing having its lower end provided with projections adapted to rest on said lugs, the lugs at one side of the stand being of more nearly closed form than at the other 20 side of the stand, and means for latching the casing in engagement with the lugs at said other side of the stand.

WILLIAM F. DEWEY.
